Primary Examiner — Mary Ann Calabrese*Assistant Examiner* — Jennifer L Rempfer(74) *Attorney, Agent, or Firm* — Cantor Colburn LLP(57) **CLAIM**

The ornamental design for a clip for portable information terminal, as shown and described.

DESCRIPTION

FIG. 1 is a perspective view of a clip for portable information terminal, showing my new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof as shown in a user environment.

The broken lines of the information terminal in FIG. 8 are for environmental purposes only and form no part of the claimed design. The broken lines showing portions of the clip for portable information terminal form no part of the claim.
